United States Patent

Des. 235,827
Patented July 15, 1975

235,827

CHAIR

George Mergenov, Closter, N.J., assignor to Mohasco
Industries, Inc., Amsterdam, N.Y.

Filed Feb. 15, 1974, Ser. No. 443,062

Term of patent 14 years

Int. Cl. D6—01

U.S. Cl. D6—69

The figure is a perspective view of a chair illustrating my new design.

The back of the chair is conventionally plain while the side not shown is substantially identical to the side shown.

I claim:

The ornamental design for a chair, as shown and described.
